(57) **CLAIM**

The ornamental design for an projection wall system, as shown and described.

DESCRIPTION

FIG. 1 is a perspective view of a projection wall system showing our new design;

FIG. 2 is front elevation view of the projection wall system illustrated in FIG. 1.

FIG. 3 is top plan view of the projection wall system illustrated in FIG. 1.

FIG. 4 is a bottom plan view of the projection wall system illustrated in FIG. 1.

FIG. 5 is a left side elevation view of the projection wall system illustrated in FIG. 1.

FIG. 6 is a right elevation view of the projection wall system illustrated in FIG. 1.

FIG. 7 is a back elevation view of the projection wall system illustrated in FIG. 1; and,

FIG. 8 is perspective view of the projection wall system illustrated in FIG. 1 in a deployed position.
